ACOUSTIC TILE

Clayton A. Laughlin, Minneapolis, Minn., assignor to
Wood Conversion Company, St. Paul, Minn., a corpo-
ration of Delaware

Application February 27, 1958, Serial No. 49,837
Term of patent 14 years

(Cl. D18—2)

Fig. 1

Fig. 2

Fig. 1 is a plan view of an acoustic tile showing my new design; and

Fig. 2 is a cross-sectional view taken on line 2—2 of Fig. 1.

I claim:

The ornamental design for an acoustic tile, substan-
tially as shown.
